UNITED STATES PATENT OFFICE.

JOHN HOUGHTON CLARKE, OF FRAMINGHAM, MASSACHUSETTS.

DESIGN FOR A HAT-FASTENER.

SPECIFICATION forming part of Design No. 28,791, dated June 7, 1898.

Application filed June 9, 1897. Serial No. 640,071. Term of patent 14 years.

To all whom it may concern:

Be it known that I, JOHN HOUGHTON CLARKE, a citizen of the United States, residing at Framingham, in the county of Middlesex and State of Massachusetts, have invented and produced a new and original Design for Hat-Fasteners, of which the following is a specification, reference being had to the accompanying drawing, which shows in perspective the design for the hat-fastener.

The design comprehends a representation of a winged insect consisting of what represents an elongated body terminating in an enlargement formed in imitation of the head of the insect, provided with curved filaments representing the antennae of an insect. Secured to a ring surrounding the body in rear of the portion representing the head and on opposite sides thereof are extended or outstretched wings, provided at their outer ends each with a figure resembling a medallion or scroll, and depending from a ring surrounding the body are outwardly and rearwardly extending portions representing the legs and terminating in enlarged ends pointed at their outer extremities. The legs from the point of attachment to the body diverge toward their outer ends and intermediate the point of attachment, and said ends are bent inwardly, converging toward the ends, thereby giving them the angular form shown.

Having thus described my design, what I claim is—

The design for a hat-fastener, substantially as herein shown and described.

In testimony whereof I have signed this specification in the presence of two subscribing witnesses.

JOHN HOUGHTON CLARKE.
